PULVERIZER

Thomas H. Arnold, Cherubsco, Mexico, assignor
to The Babcock & Wilcox Company, Newark,
N. J., a corporation of New Jersey

Application April 2, 1942, Serial No. 437,330

13 Claims.

(Cl. 241—61)

The present invention relates to the construction and operation of pulverizers of the type designed for pulverizing coal, cement materials and the like and in which the pulverized material is removed from the grinding zone of the pulverizer in suspension in a gaseous carrier medium.

The general object of my invention is the provision of a pulverizer of the type described which is characterized by the high degree of fineness of the pulverized material discharged and the relatively low power consumption of the pulverizer. A further and more specific object is the provision of an improved rotary classifier construction and arrangement for a pulverizer of the type described which greatly contributes to the fineness of the output.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation of a pulverizer constructed in accordance with my invention.

Fig. 2 is an enlarged view of the classifier section of Fig. 1; and

Fig. 3 is a fragmentary plan view of the rotary classifier.

The pulverizer illustrated is of the general type disclosed and claimed in U. S. Patent 2,275,595, granted March 10, 1942, and as shown in Fig. 1 comprises a substantially cylindrical housing 10, the base of which includes the drive assembly for a vertical drive shaft 11. The shaft 11 has a conical yoke 12 keyed on its upper end. The grinding parts of the pulverizer comprise a lower rotary grinding ring 13 carried on the lower outer end of the yoke, a circular row of grinding balls 14 arranged in a track on the ring 13, and a spring pressed non-rotary upper ring 15 carried on the ball row. The material to be pulverized is delivered through a feed spout 16 opening through the top wall 17 of the housing adjacent its periphery. The spout is extended downwardly to deliver the material to the yoke 12 at the inner side of the ball row. In operation the material flows outwardly over the lower grinding ring where it is pulverized between the relatively moving balls and grinding rings.

An annular windbox 20 connected to a source of preheated air opens to the housing at the outer side of the grinding ring 13. The annular air stream flows upwardly through a Venturi-shaped throat 21 formed between the outer side of the ring 13 and an annular throat plate 22 having a

segmental relief gate 23 in one part thereof. The pulverized material leaving the outer edge of the lower grinding ring is swept up by the high velocity air stream and carried upwardly in suspension into the portion of the housing above the grinding zone.

The housing top is formed by the annular plate 17 and a raised cylindrical center section or turret 25 forming a cylindrical chamber 26 as a continuation of the central opening in the plate 17. An opening 27 is formed in the top of the turret for the discharge of material-laden air. During the passage of the material-laden air upwardly along the side walls of the housing some of the oversize particles separate from the air stream and drop back into the grinding zone. Before the material-laden air can enter the turret section it is subjected to the action of a rotary classifier symmetrically arranged relative to the outlet 27.

The rotary classifier is formed by upper and lower horizontally arranged annular plates 31 and 32 respectively. The plate 31 extends beyond the circumference of the plate 32 and at its inner periphery has an uprising circular flange 33 which extends into the opening in the top plate 17. A circular series of fan or impact blades 35 is symmetrically arranged in an inverted frusto-conical formation between the plates 31 and 32. The classifier blades are preferably of angular cross-section, as shown in Fig. 3, and welded at their ends to the plates 31 and 32. The angular blades have an angle of approximately 90° between their sides and are arranged to form a series of angularly spaced pockets facing in the designed direction of rotation of the classifier indicated by the arrow in Fig. 3. With this construction and arrangement oversize particles in the air stream tend to collect in the blade pockets and slide downwardly along the pocket to the plate 32 and thus out of the path of the stream of material-laden air passing through the classifier.

The classifier is detachably mounted on a supporting structure carried by the drive yoke 12. The classifier support 37 forms a downwardly tapering continuation of the opening in the plate 32 to receive oversize material dropping out of the classifier. The material deposits on the top of the drive shaft and on a support base plate 38 and is discharged from that area through slots 50 between rectangular plates 39 as in said Patent No. 2,275,595. The discharged oversize particles are returned to the grinding zone for further pulverization.

In operation the classifier blades give the material-laden air stream a swirl as it passes into the turret chamber 26. This swirling action throws the coarse material towards the sides of the turret chamber and tends to produce eddy currents in the upper circumferential corner of the chamber which cause the coarse material to

move downwardly in a relatively dense stream along the side wall of the chamber. In order to reduce the static pressure drop through the turret outlet 27, a cone member 40 is positioned in the opening 21 so as to form an upwardly tapering entrance to the outlet 27. The cone 40 is vertically adjustable relative to the turret section by means of supporting hangers 41 extending through the top wall of the turret and externally adjustable. This arrangement of the cone aids in confining the eddy currents to the upper corner of the turret chamber.

The coarse particles descending along the sides of the turret would ordinarily accumulate on the classifier top plate 31 and spill over into the air stream leaving the inner side of the classifier and recirculate in the turret chamber or be carried out through the discharge outlet 27. In accordance with my invention the upper portion of the classifier is constructed and arranged to receive any coarse material separated in the turret section and return the same to the grinding zone. As shown in Fig. 2, the classifier upper plate 31 is arranged slightly below and inwardly of the central opening in the housing top plate 17. A circular series of angularly spaced symmetrically arranged bars 45 are mounted on the upper surface of the classifier plate 31 and welded thereon in a position in which the inner end of each bar is the leading end and the bar is tangentially arranged relative to a circle of slightly smaller diameter than the plate flange 33. A flat annular seal plate 46 is mounted on the outer section of the bars 45 in a position in which the circumferential outer edge of the plate 46 has a slight clearance relative to the top plate 17 and the inner circumferential edge is spaced from the classifier top plate flange 33 leaving an annular opening 47 therebetween through which coarse material from the turret chamber can drop onto the top plate 31 and be forced outwardly therefrom when the classifier is in operation by the blade action of the obliquely arranged bars 45. A centrifugal effect is thus imposed on the coarse particles sufficient to overcome the pressure differential through the classifier. The circumferentially discharged material is directed downwardly by a frusto-conical plate 48 on the underside of the housing top plate 17.

The coarse particles separated in the turret chamber are thus directed towards the grinding zone of the pulverizer, thereby increasing the fineness of the output through the discharge cone 40. The increased fineness of the output is demonstrated by test results on a coal pulverizer of the character described used in a cement kiln direct firing pulverized coal system, before and after the installation of a classifier construction and arrangement in accordance with my invention:

Fineness	Original installation	Present arrangement
	Per cent	Per cent
Through 50 mesh	99.95	100
Through 100 mesh	99.52	99.94
Through 150 mesh	96.44	99.48
Through 200 mesh	85.14	95.56
Through 325 mesh	74.0	88.38

In the operation of my invention the coarse material in effect is stripped from the circumference of the whirling stream of air and material in the turret chamber. This separating action can be varied by altering the width of the bars 45 to thus alter the quantity of air and

material drawn from the stream to carry the particles out of the main stream. The height of the classifier top plate flange 33 controls the amount of coarse particles spilled back into the air stream passing upwardly at the inner side thereof and variations in this height will change this condition. A substantial increase in fineness of the pulverizer output is thus obtainable with the described construction and arrangement, while at the same time the wear on the classifier top plate due to coarse material accumulating and riding around thereon is substantially eliminated.

While in accordance with the provisions of the statutes I have illustrated and described herein the best form of my invention known to me, those skilled in the art will understand that changes may be made in the form of the apparatus and character of the carrier medium disclosed without departing from the spirit of the invention covered by the claims, and that certain features of the invention may sometimes be used without a corresponding use of other features. In the claims, the word "air" is intended to generically cover any gaseous carrier medium suitable for removing pulverized material in the manner described.

I claim:

1. In a pulverizer comprising a housing enclosing grinding parts forming a grinding zone, means for delivering material to be pulverized to said grinding zone, means for directing an air stream upwardly through said grinding zone to sweep up pulverized material discharging therefrom, and an opening in the top of said housing, the combination of a turret forming an upward continuation of said opening and having a discharge outlet, a rotary member symmetrically arranged at the lower end of said housing opening and having an annular plate within the periphery of said housing opening, and means on said plate for circumferentially discharging coarse particles separated in said turret and depositing on said plate.
2. In a pulverizer comprising a substantially cylindrical housing enclosing grinding parts forming a grinding zone, means for delivering material to be pulverized to said grinding zone, means for directing an air stream upwardly through said grinding zone to sweep up pulverized material discharging therefrom, and an opening in the top of said housing, the combination of a cylindrical turret forming an upward continuation of said opening and having a discharge outlet in the top thereof, a rotary classifier symmetrically arranged at the lower end and within the periphery of said housing opening and having upper and lower annular plates, a circular series of impact blades extending between said plates, and means on the upper side of said upper classifier plate for deflecting coarse particles depositing on said upper plate towards said grinding zone.
3. In a pulverizer comprising a housing enclosing grinding parts forming a grinding zone, means for delivering material to be pulverized to said grinding zone, means for directing an air stream upwardly through said grinding zone to sweep up pulverized material discharging therefrom, and an opening in the top of said housing, the combination of a turret forming an upward continuation of said opening and having an air discharge outlet, a rotary classifier arranged within the periphery of said housing opening and

having upper and lower annular plates, a circular series of impact blades extending between said plates, and material directing means on the upper plate of said classifier for deflecting coarse particles separated in said turret towards said grinding zone, said upper plate and said material directing means thereon having at least a substantial part thereof extending within the periphery of said housing opening.

4. In a pulverizer comprising a housing enclosing grinding parts forming a grinding zone, means for delivering material to be pulverized to said grinding zone, means for directing an air stream upwardly through said grinding zone to sweep up pulverized material discharging therefrom, and an opening in the top of said housing, the combination of a cylindrical turret forming an upward continuation of said opening and having a flat top plate with a central discharge outlet therein, a rotary classifier symmetrically arranged at the lower end of said housing opening and having upper and lower annular plates, a circular series of impact blades extending between said plates, a conical member forming a downwardly flaring extension of said turret outlet, and means on the upper plate of said classifier for deflecting coarse particles separated in said turret and depositing on said upper plate towards said grinding zone.

5. In a pulverizer comprising a housing enclosing grinding parts forming a grinding zone, means for delivering material to be pulverized to said grinding zone, means for directing an air stream upwardly through said grinding zone to sweep up pulverized material discharging therefrom, and a central opening in the top of said housing, the combination of a cylindrical turret forming an upward continuation of said opening and having a central discharge outlet in the top thereof, a rotary classifier symmetrically arranged at the lower end and within the periphery of said housing opening and having upper and lower annular plates, a circular series of angular impact blades extending between said plates, a conical member forming a downwardly flaring extension of said turret outlet, and means on the upper plate of said classifier for deflecting coarse particles separated in said turret towards said grinding zone including an upwardly extending flange on the inner periphery of said upper plate and a series of obliquely extending bars on the upper side of said upper plate.

6. In a pulverizer comprising a substantially cylindrical housing enclosing grinding parts including a vertical drive shaft, a lower grinding ring operatively connected to said drive shaft, a non-rotary upper grinding ring, and a circular row of rolling grinding elements between said grinding rings, means for delivering material to be pulverized to the inner side of said row, means for directing an annular air stream upwardly past the outer side of said grinding parts to sweep up pulverized material discharging therefrom, and a central discharge opening in the top of said housing, the combination of a cylindrical turret surrounding said opening and having an outlet in its top, a rotary classifier below said housing opening and operatively connected to said drive shaft, said classifier having upper and lower annular plates arranged within the periphery of said housing opening, a circular series of angularly spaced blades extending between said plates, and means on the upper plate of said classifier

for directing coarse particles separated in said turret towards said housing grinding zone.

7. In a pulverizer comprising a substantially cylindrical housing enclosing grinding parts including a vertical drive shaft, a lower grinding ring operatively connected to said drive shaft, a non-rotary upper grinding ring, and a circular row of rolling grinding elements between said grinding rings, means for delivering material to be pulverized to the inner side of said row, means for directing an annular air stream upwardly past the outer side of said grinding parts to sweep up pulverized material discharging therefrom, and a central discharge opening in the top of said housing, the combination of a cylindrical turret surrounding and forming a continuation of said opening and having an outlet in its top, a rotary classifier below said housing opening and operatively connected to said drive shaft, said classifier having upper and lower annular plates, a circular series of blades extending between said plates, a conical member forming a downwardly flaring extension of said turret outlet, and means on the upper plate of said classifier for deflecting coarse particles separated in said turret and depositing on said upper plate towards said housing grinding zone.

8. A rotary classifier adapted to rotate about a vertical axis and comprising horizontally arranged upper and lower concentric annular plates, a circular series of angularly spaced blades extending between said plates, and bars on the upper side of said upper plate arranged substantially tangential to the inner circumference of said upper plate with their inner ends leading in the direction of rotation of said upper plate for outwardly deflecting separated material depositing on said upper plate.

9. A rotary classifier adapted to rotate about a vertical axis and comprising horizontally arranged upper and lower concentric annular plates of different diameters, a circular series of angularly spaced blades extending between said plates in an inverted frusto-conical formation, and bars on the upper side of said upper plate, arranged substantially tangential to the inner circumference of said upper plate with their inner ends leading in the direction of rotation of said upper plate for outwardly deflecting separated material depositing on said upper plate.

10. A rotary classifier adapted to rotate about a vertical axis and comprising horizontally arranged upper and lower concentric annular plates of different diameters, a circular series of angularly spaced blades extending between said plates in an inverted frusto-conical formation, and means on the upper side of said upper plate for outwardly deflecting material depositing on said upper plate including an upwardly extending flange on the inner periphery of said upper plate and obliquely arranged bars secured to the upper side of said upper plate at the outer side of said flange.

11. A rotary classifier adapted to rotate about a vertical axis and comprising horizontally arranged upper and lower concentric annular plates of different diameters, and a circular series of angularly spaced impact blades extending between said plates in an inverted frusto-conical formation, said blades having a V-shaped transverse cross-section and arranged with their apex lines in radial planes and forming material-receiving pockets opening in the direction of rotation of the classifier.

12. In combination, a housing having a dis-

charge opening in its upper end for a gas carrying particles of finely divided material in suspension, a turret forming an upward continuation of said housing opening and having a gas discharge outlet, a rotary classifier positioned at the lower end of said housing opening and having an upper annular plate arranged within the periphery of said housing opening, a circular series of spaced blades connected to said plate, and means on the upper side of said classifier plate for directing coarse particles separated in said turret and depositing on said plate into said housing.

13. In combination, a housing having a circular discharge opening in its upper end for a

gas carrying particles of finely divided material in suspension, a cylindrical turret forming an upward continuation of said housing opening and having a gas discharge outlet in the top thereof, a rotary classifier symmetrically arranged relative to said housing opening and having an upper annular plate arranged within the periphery of said housing opening, a lower plate, a circular series of spaced blades extending between said plates, and means on the upper side of said upper classifier plate for directing coarse particles separated in said turret and depositing on said upper plate into said housing.

THOMAS H. ARNOLD.
